FRANGIBLE CLOSURE FOR CONTAINERS

Otto F. Blom, New York, N. Y., assignor to American Can Company, New York, N. Y., a corporation of New Jersey

Application December 16, 1944, Serial No. 568,505

5 Claims. (Cl. 220—27)

1

The present invention relates to containers or cans and has particular reference to a friction plug type can having a frangible seal that serves as a gasket for the friction can cover.

An object of the invention is the provision of a friction plug container having a frangible seal wherein a portion of the frangible seal functions as a gasket for the friction plug cover on the container to render the closure airtight even after the frangible seal has been broken to gain access to the container contents and the friction plug cover has been utilized as a reclosure member.

Another object is the provision of such a container wherein a full open mouth may be had without impairing the functioning of the frangible seal as a gasket so that repeated ready access may be had to the interior of the container and so that liquid contents may be readily poured therefrom if desired.

Another object is the provision of a container of this character wherein a friction plug cover may be used in the full open mouth of a container without the use of a friction ring, the frangible seal providing a resilient gasket between the container body and the cover when the latter is used as a reclosure and which renders the closure leak-proof even at the side seam of the body.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a container embodying the instant invention; and

Fig. 2 is an enlarged vertical sectional view of a portion of the upper end of the container.

As a preferred embodiment of the invention the drawings illustrate a sheet metal cylindrical container adapted to hold paint or other liquid materials although the invention is equally well adapted to containers of other shapes and materials and for other products, such as dry and frozen food products and the like.

The container illustrated in the drawings comprises a cylindrical body 11 having a bottom 12 secured thereto in any suitable manner such as by an end seam 13. The upper end of the body 11 preferably is reduced in diameter to form a necked-in vertical wall section 15, the inner surface of which defines a mouth or opening 16 (Fig. 2) for the container.

Adjacent the upper edge of the container body the necked-in wall section 15 merges into a substantially horizontal, outwardly extending annu-

2

lar shoulder or seat wall section 17. This seat wall section merges into an upwardly and inwardly curved clamping wall section 18 constituting an outwardly extended body loop portion which in turn slopes downwardly toward the seat wall section adjacent its inner edge and terminates in an upwardly and outwardly bent body curl 19. The inner edge of this curl is substantially flush with the plane of the inner surface of the necked-in body wall section 15, and the outer extremity of the body loop portion 18 is substantially flush with the vertical plane of the body wall part 11 of the major diameter.

The seat wall section 17 and the oppositely disposed clamping wall section 18 hold in place a dish shaped frangible seal 21 (Fig. 2) disposed within the mouth 16 of the container. This frangible seal preferably is made of treated fibre although it may be made of other materials, such as soft metal, cellulosic and plastic materials and the like. The term "treated" designates a state wherein the fibre wall is impervious to liquids and gases, i. e. is airtight.

The frangible seal 21 comprises a vertical annular friction wall section 22 which snugly engages against the inner surface of the necked-in wall section 15. At its upper end the annular wall section 22 merges into a flange 23 which is formed with a hem 24 folded back on top of the flange. The hem preferably terminates short of the width of the flange. The seal flange rests on the seat wall section 17 of the can body while the hem 24 engages against the clamping wall section 18, the curl 19 of the body wall engaging against the short terminal edge of the hem. In this manner the flange and the hem, forming a double thickness wall section on this seal, are held in tightly clamped position between the seat wall section 17 and the clamping wall section 18 of the container body.

Adjacent its lower or inner end, the vertical wall section 22 of the frangible seal 21 merges into an inwardly and upwardly curved annulus 26 which extends inwardly into a flat bottom 27. The annulus 26 sets off an annular groove 28 around the outer edge of the bottom 27 and thus in effect makes the bottom of the seal a raised panel. With this construction the container is hermetically sealed.

A countersunk friction plug cover 31 preferably made of metal is provided for the container. This cover protects the frangible seal 21 during shipment and storage and also serves as a hermetic reclosure for the container after it is once opened. The cover is formed with a substantially vertical

friction wall section 32 which at its lower end merges into a countersunk panel or bottom 33. Adjacent its upper end the friction wall 32 is formed with an annular flange 34 having a reinforcing hem 35 bent back against the under or lower surface of the flange.

When in container sealing position, the cover 31 is disposed within the mouth of the container with its vertical wall section 32 in tight fitting engagement with the vertical wall section 22 of the frangible seal 21. The cover flange 34 engages against the curl 19 of the can body and the bottom 33 of the cover is in closely spaced relation to the panel 27 of the frangible seal as shown in Fig. 2. In this fully inserted position the cover protects the frangible seal 21 from being bulged out too far or from being broken by the force of the contents of the container during shipment or storage.

The vertical friction wall section 22 of the frangible seal functions as a resilient gasket between the cover side wall 32 and the body side wall 15. Functioning as a gasket the frangible seal provides a hermetic joint between the cover and the body, especially at the side seam of the body where leaks usually occur in a container of this character when the gasket of the instant invention is not used. It should be here noted that there is a slight clearance between the body curl 19 and the vertical wall section 32 of the cover to insure sealing engagement between the cover and the frangible seal.

To open the container, the cover is pried off, and the bottom of the frangible seal 21 is cut or broken out. Cutting out of the seal preferably is effected along a line of severance in the bottom groove 28 and near the lower end of the vertical wall section 22. A score line 37 may be provided in the frangible seal to facilitate the breaking action. In either case, the removal of the bottom of the frangible seal, results in substantially a full open mouth in the upper end of the container so that ready access to the contents or pouring of the contents may be accomplished. This removal of the bottom portion of the seal leaves intact its vertical wall section 22. This wall section continues to function as a hermetic gasket seal for the cover 31 when the latter is used as a reclosure cover to hermetically reseal the container after being once opened.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container comprising a body having an opening and an outwardly extending open loop portion in the body wall adjacent said opening, an imperforate friction plug reclosure cover having a vertical friction wall fitting within said opening, and an imperforate frangible seal having its outer periphery clamped within said body loop and thence extending down into and across said opening beneath said cover for hermetically sealing the container, said frangible seal also surrounding the vertical friction wall of said cover to constitute a gasket for the cover to hermetically reseal the container when the cover is used as a reclosure after the frangible seal is broken.

2. A container comprising a body having a body wall defining an opening and an outwardly extending open loop portion in the body wall adjacent said opening, a dish shaped frangible seal having its peripheral edge clamped within said body loop portion, said frangible seal having an annular vertical side wall portion extending down into said body in engagement with the inner wall surface thereof, said seal having a raised bottom panel wall extending across said opening for hermetically sealing said container, said bottom panel of the seal being connected to its said vertical side wall portion by a channel shaped annulus providing for a line of severance for cutting out the bottom panel to open said container, and a plug reclosure cover having an annular vertical friction wall insertable into the vertical side wall portion of said frangible seal in tight fitting engagement, said seal constituting a hermetic gasket between the cover and the body before removal of the bottom of said seal to protect the seal during shipment and storage, said frangible seal side wall portion after removal of the seal constituting a gasket to hermetically protect any contents remaining in the container after initial opening.

3. A container comprising a body having a body wall defining an opening, a dish shaped imperforate frangible seal having its peripheral edge portion clamped within an outwardly extending loop portion of said body wall, said frangible seal having an annular side wall section extending down into said body in engagement with the inner surface of said body wall section and having a raised bottom panel wall section extending across said opening for hermetically sealing said container, said bottom panel being connected to said side wall section by a channel shaped annulus, a score line in said annulus providing a weakened area for breaking out the bottom panel to open said container, and an imperforate friction plug reclosure cover having a vertical annular friction wall and a closed countersunk bottom insertable into said frangible seal in tight fitting engagement with its annular side wall section, the latter constituting a hermetic gasket between the cover and the body before removal of the bottom of said seal to protect the seal during shipment and storage and also after removal of the bottom of the seal to hermetically protect any contents remaining in the container after initial opening.

4. A container comprising a body having a body wall defining an opening and an outwardly extending open loop portion in the body wall adjacent said opening, a dish shaped frangible seal having its peripheral edge portion clamped within said body loop portion, said frangible seal having an annular side wall portion extending down into said body wall in close engagement with its inner surface, said seal having a bottom wall section extending across said opening for hermetically sealing said container, and a friction plug reclosure cover including a countersunk bottom merging into a surrounding upright wall portion in turn terminating in a hemmed flange, said cover being insertable into the opening of said body with its upright wall portion in tight fitting engagement with the side wall portion of said frangible seal, the latter serving as a resilient hermetic gasket between the cover and the body.

5. A container comprising a body having an opening and an outwardly extending open loop portion in the body wall adjacent said opening, an imperforate frangible seal having its periph-

ery clamped within said body loop portion and thence extending down into and across said opening for sealing said container, and a container cover having a depending wall disposed in frictional engagement with the downwardly extending portion of said seal, said frangible seal functioning as a gasket for said cover when the latter is inserted as a reclosure into said opening to hermetically reseal the container after the frangible seal is broken.
